ATTORNEY

UNITED STATES PATENT OFFICE.

JAMES N. DIXON, OF RICHMONDDALE, OHIO.

DUMPING-WAGON.

SPECIFICATION forming part of Letters Patent No. 693,246, dated February 11, 1902.

Application filed May 31, 1900. Serial No. 18,545. (No model.)

To all whom it may concern:

Be it known that I, JAMES N. DIXON, a citizen of the United States, residing at Richmonddale, in the county of Ross and State of Ohio, have invented a certain new and useful Improvement in Dumping-Wagons, of which the following is a specification.

My invention relates to the improvement of dumping-wagons, and has particular relation to the improvement of that class of wagon-beds which are adapted for carrying gravel, sand, &c.

The objects of my invention are to provide a wagon-bed of superior construction and arrangement of parts with improved means for dumping or discharging the load therefrom and to produce certain improvements in details of construction, which will be more fully pointed out hereinafter. These objects I accomplish in the manner illustrated in the accompanying drawings, in which—

Figure 1 is a view in perspective of a wagon-bed having my improvements and showing the body-bottom sections turned in positions for discharging the contents of the wagon. Fig. 2 is a central longitudinal section of said bed, and Fig. 3 is a transverse section of the same.

Similar numerals refer to similar parts throughout the several views.

In the illustrations, 1 and 2 represent the front and rear end body-bolsters, 3 the parallel bed side-boards, and 4 and 5 the inclined front and rear end-boards. Upon each of the bolsters 1 and 2 I support a transverse bearing-bar 6, the latter being provided in its upper side at intervals with vertical bearing-recesses 7. In these recesses bear the rounded upper side end extensions 8 and 9 of parallel floor slats or sections 10, the bodies of which extend, as shown, between the bearing-bars 6. These floor-sections are of such width and relative arrangement that when the same are turned in their bearings until their sides are flush a complete floor for the wagon-bed is formed. The forward bearing extensions 9 of the floor-sections are extended, as shown, beyond the forward end of the wagon-bed, said extensions having mounted thereon short arm projections 11, which extend at right angles with the directions of the lengths of said floor-sections. The outer end portions of

these arms 11 have pivotally connected therewith a transverse bar 12. The central one of the arms 11 is extended to form a lever 13, 55 the bar 12 being pivoted to the lower portion thereof. Suitably journaled on the upper sides of the side-boards 3 and extending transversely across the top of the wagon-bed is a rod 14, one end of which is provided with a short arm 15, extending in a direction at right angles with said rod, and the remaining end of which is connected with the angle of a bell-crank lever 16, the longer arm of said lever forming an operating-handle 17 60 and the lower and shorter arm of said lever having pivotally connected therewith the upper end of a rod 18, which extends downward through a suitable keeper 19, which projects from the side of the wagon-bed and is secured to one end of a transverse bar 20, which extends beneath the wagon-bed. The opposite end of said bar 20 has connected therewith an upwardly-extending rod 21, which, as shown in full and dotted lines in Fig. 1 of the 75 drawings, has its upper end connected with the short arm 15 of the rod 14. Between the forward ends of the wagon and the lever 16 I provide one of the side-boards 3 in its upper portion with a downturned catch-hook 22. 80

In the drawings I have shown the floor-sections turned downward or with their wider sides parallel, in which position it is obvious that any material contained in the wagon-bed may drop through to the ground between said sections. In order to restore the sections 10 to their normal and closed positions and provide a substantially solid or integral flooring for the wagon-bed, the lever 13 is first thrown toward that side of the bed which is provided 85 with the lever 16 until the wider sides of said sections 10 are flush and the bottom of the bed is closed. The lever 17 is then turned forwardly and its handle portion caused to engage the hook 22. In this forward movement of the lever 17 it will be seen that the cross-bar 20 will be lifted until in contact with the under sides of the sections 10 and the latter thus prevented from voluntarily swinging downward. It being desired to open the 90 bed-bottom until the sections are in the positions indicated in the drawings for the purpose of dumping the load between the same, it is evident that the operation consists in re-

leasing the lever 17 from the hook 22, allowing the bar 20 to descend, and the lever 13 to incline in the direction indicated in Fig. 1 of the drawings.

5 From the above construction and operation it will be seen that a simple, reliable, and effective dumping-wagon bed is provided and that superior means are produced for opening or closing the bottom of the bed at the will of the operator.

Having now fully described my invention, what I claim, and desire to secure by Letters Patent, is—

In a dumping-wagon bed, the combination

with the bed-frame, parallel floor-sections 10 15 journaled in said bed-frame, said sections having bearing extensions 9, arms fixed on said bearing extensions, one of said arms being extended to form a lever and a bar 12 20 jointedly connecting said arms, of a bar 20 extending beneath said floor-sections and supported from said bed and means for raising and lowering said bar, substantially as specified.

JAMES N. DIXON.
